Attorney, Agent, or Firm—William A. Simons; Thomas F. Presson; Wiggin & Dana

[57] **CLAIM**

The ornamental design for a container cover, as shown and described.

DESCRIPTION

FIG. 1 is a perspective view of the container cover;
 FIG. 2 is a front elevational view of the container cover, the front and back of the container cover being mirror images of each other;
 FIG. 3 is a side elevational view of the container cover as seen from the left hand side of FIG. 2;
 FIG. 4 is a side elevational view of the container cover as seen from the right hand side of FIG. 2;
 FIG. 5 is a top plan view of the container cover; and,
 FIG. 6 is a bottom plan view of the container cover.
 Structure shown in broken lines in the drawings is for illustrative purposes only and does not form a part of the claimed design.
